Attorneys

UNITED STATES PATENT OFFICE.

JAMES BIRDSALL CALKINS, OF ITHACA, NEW YORK.

WINDING APPARATUS.

Application filed October 3, 1924. Serial No. 741,380.

This invention relates to certain improvements in winding apparatus, and is here illustrated in its adaptation to spinning jennies, altho it is applicable for use in connection with twisters, formers, layers, roving frames, spinning frames, etc. in which the product, while being revolved around a common axis to give it its twist, is presented to the coil, cop or ball and wound thereon.

The apparatus illustrated is particularly adapted for winding twine, thread, yarn or rope, or the like, in cylindrical, conical or otherwise shaped coils, in such a manner that the ends of the coils will be self supporting and so that the distance between any two successive turns of the twine etc. will be substantially the same, regardless of the diameter of the coil or ball. In order to obtain a coil or ball of twine of desired density and uniformity of winding, it has been customary in the use of spinning jennies and other like apparatus to first wind the twine on bobbins with disks or heads at each end thereof to keep the loops of twine from coming off the end of the coil or ball and subsequently the twine was delivered from the bobbin to another winding mechanism for producing the desired coil or ball preferably of a character having self-supporting ends.

Certain of the advantages of this invention reside particularly in the elimination of the rewinding step and in the production of an apparatus by means of which the desired winding can be effected directly as the twine is delivered from the spinning or twisting equipment, which desired winding may include the self-supporting character of the ends of the coil, if desired.

The invention also permits the winding of certain types of twine, such as binder twine, in the size and shape of ball in which it is commonly sold.

Further, the invention avoids the necessity of using headed bobbins or spools and permits the use of a collapsible or other type of core of paper, wood or the like and the omission of the bobbin admits in many cases the winding of larger or more suitably shaped coils or balls, thus eliminating much rewinding and doffing.

Other objects and advantages relate to the details of form, construction, arrangement and operation of the apparatus, all as will more fully appear from the follow-

ing description, taken in connection with the accompanying drawings, in which:

The figure is a sectional view of the flyer of a spinning jenny combined with the winding device of this invention.

In order to specifically illustrate the construction and operation of this invention, it has, as above suggested, been disclosed in connection with a type of spinning jenny commonly used for spinning hemp or sisal fibre, but it will be understood that this invention is in no way limited or restricted by the above illustrative disclosure.

The operation of portions of the apparatus disclosed is that ordinarily used and well known in connection with this type of spinning jenny. By means of the constant rotative movement of the capstans —1—, driven by the relative rotation which they receive by being bodily carried around on the flyer head —2— and at the same time the incorporated gears —3— engaging pinion —4— which by means of the hollow shaft —5— is driven by a belt applied to pulley —6—, the fibre —7— is drawn through the usual nipper. At the same time by means of the belt applied to pulley —9— and the concentric shaft —10—, the fibre is twisted in the nipper and appears in its twisted form at the point —7—.

From the nipper the twine passes through the hollow shaft —5— around the capstans —1— and over the sheaves —11— and —12— to the laying device —13— and on to the coil —14—.

The operation of the structure so far described is well known. The coil-winding cylinder —15— is axially supported by the removable shaft —16— and is connected to the tubular shaft —17— for simultaneous rotation therewith in the usual manner, the tubular shaft —17— being mounted within and carried by the concentric shaft —10—.

The well-known practice of "universal winding" for which the apparatus of this invention is adapted consists of winding the twine in a coil with comparatively large pitch or distance between each successive turn, and also advancing approximately the width of the twine each successive traverse of winding as illustrated by the coil —14—, thus producing an interlocking effect which makes the coil self-supporting and eliminates the necessity of the headed bobbin or spool. To produce this effect with each successive layer of twine on a coil which is constantly

growing larger, it is evident that the laying device —13— must be moved laterally in front of the coil —14— and this traverse motion must always be proportional to the 5 number of turns of the twine that are wound on the coil in a given increment of time.

In other words, regardless of the diameter 10 of the coil, the laying device must be moved the same distance for each turn wound on the coil. However, since the twine is made at a constant rate of speed and delivered by 15 the flyer —8— at a constant rate of speed, the turns of the twine wound on the coil in a given increment of time must always be inversely proportional to the variable diameter 20 of the coil during that interval, and therefore the traverse movement of the laying device —13— must be inversely proportional to the diameter of the coil as well as directly proportional to the number of turns 25 of the twine wound on the coil in the given increment of time.

The twine imparts some of the rotative movement of the flyer —8— to the coil-winding cylinder —15— and the tubular shaft —17—, and this amount is equal to the 30 constant rotative speed of the flyer minus the number of turns of twine which have been wound on the coil in the given increment of time.

In order to produce the type of winding desired and described heretofore, the traverse movement of the laying device must always be proportional to the number of 35 turns of twine wound on the coil in the given increment of time, regardless of the diameter of the coil.

For the purpose of producing the desired speed of traverse movement of the laying 40 device —13—, the gear —18— is mounted on the tubular shaft —17— and made to rotate therewith. Engaging with the gear —18— is pinion —19— which is carried by but free to rotate around the flyer arm 45 —21— which in turn connects and is carried by the revolving flyer heads —2— and —20—. It is evident that the rotative speed of the pinion —19— around its own axis is proportional to the difference between the 50 speed that it is bodily carried around by the flyer heads —2— and —20— on the flyer arm —21— and the speed of the engaging gear —18— since both rotative movements are in the same direction. These two speeds 55 represent respectively the speed of the flyer and the speed of the winding cylinder, and as stated above, the speed of the winding cylinder is variable but always equal to the speed of the flyer minus the number of turns 60 wound on the coil in the given increment of time. Therefore, the difference between these two speeds or the rotative speed of the pinion —19— is proportional to the number 65 of turns wound on the coil in any increment of time.

To illustrate this better, suppose we let R represent the rotative speed of the flyer or the speed that the pinion —19— is carried around bodily by the flyer heads —2— and —20— on the flyer arm —21—. Also 70 let W represent the number of turns of twine wound on the coil in any increment of time. Then the rotative speed of the gear —18— will be proportional to F—W. Therefore, the rotative speed of the pinion —19— will be proportional to F—(F—W) 75 which reduces to W.

As stated before, the traverse movement of the laying device must be proportional to the number of turns of twine wound on the coil in the given increment of time, or W, 80 and we have proven above that the rotative speed of the pinion —19— is proportional to W. Therefore, by selecting the proper ratio between the gear —18— and the pinion —19— to accompany the pitch of the traverse screw —22— which is cut on the extended hub of the pinion —10— any desired pitch of winding the twine on the coil —14— can be accomplished by causing the 85 traverse fork —23— carried in the hub of the laying device —13— to engage the thread of the double traverse screw —22—. In other words, the laying device —13— is carried back and forth in front of the coil 90 —14— by the action of the traverse screw —22— engaging the traverse fork —23— and since the screw rotates at a speed proportional to the number of turns of twine 95 wound on the coil in the given increment of time regardless of the diameter of the coil, the laying device likewise will pass back and forth in front of the coil at a speed always proportional to the number of turns wound on the coil in the given increment of 100 time. This produces the desired type of winding known as "universal winding" and described heretofore.

In order to provide sufficient tension in the twine so that it will be wound in a hard, 110 smooth coil, suitable means should be provided for resisting the rotary movement of the shaft —17— which is driven by the twine through the coil-winding cylinder —15—.

To accomplish this, pulley —24— may be mounted on the end of and made to rotate with shaft —17—. The braking effect may be accomplished in any suitable way such as applying friction directly to the pulley —24—, or what is more common, belting it to a differential friction device which it is not necessary to describe since it is used very extensively for spinning jennies of this type, 120 and since it has no bearing on the claims of this invention.

Altho I have shown a specific application of my invention to a particular machine, together with perhaps preferred details of 125 form, construction or arrangement of the 130

same, I do not desire to restrict myself to any particular application of the invention or arrangement of the same, except as the same may be specifically required by the 5 claims hereto appended.

I claim:

1. In a winding apparatus, the combination with the flyers of such an apparatus including opposite heads, and flyer arms 10 connecting the heads, of a receiving element about which a coil is adapted to be wound, a sleeve mounted upon one of the flyer arms and freely rotatable about said arm and formed with a traverse screw, a gear concentric with the sleeve and connected to the sleeve for driving the latter, a second gear 15 rotating with the receiving element and adapted to drive the first-named gear, and a laying device movable transversely of the receiving element at a speed dependent upon the speed of rotation of the traverse screw.
2. In a winding apparatus, the combination with the flyers of such an apparatus including opposite heads and flyer arms connecting the heads, of a receiving element 20 about which a coil is adapted to be wound, a sleeve mounted upon one of the flyer arms and freely rotatable about said arm and

formed with a traverse screw, a gear concentric with the sleeve and connected to the sleeve for driving the latter, a second gear 30 rotating with the receiving element and in mesh with the first-named gear for driving the latter, and a laying device movable transversely of the receiving element at a speed dependent upon the speed of rotation 35 of the traverse screw.

3. In a winding apparatus, the combination with the flyers of such an apparatus including opposite heads and flyer arms connecting the heads, and a receiving element 40 about which a coil is adapted to be wound, of a traverse screw in connection with one of the flyer arms, a gear concentric with 45 the traverse screw and connected to the traverse screw for driving the latter, a laying device driven by the traverse screw, a gear concentric with the receiving element and driven by the latter and in constant 50 mesh with the first-named gear for causing the traversing movement of the laying device at a speed proportional to the number of turns wound on the receiving element.

In witness whereof I have hereunto set 55 my hand this 20 day of September, 1924.

JAMES BIRDSALL CALKINS.
